DESIGN FOR A TOILET-SET.

Design No. 12,232, dated April 26, 1881.

UNITED STATES PATENT OFFICE.

ISAAC DAVIS, OF TRENTON, NEW JERSEY.

DESIGN FOR A TOILET-SET.

SPECIFICATION forming part of Design No. 12,232, dated April 26, 1881.

Application filed March 9, 1881. Term of patent 3½ years.

To all whom it may concern:

Be it known that I, ISAAC DAVIS, of the city of Trenton, in the county of Mercer and State of New Jersey, have invented a new and original Design for Toilet-Sets, of which the following is a full, clear, and exact description, reference being had to the photographic illustrations, which form a part of this specification.

My invention relates to a new and ornamental design for the body of the vessels composing such sets; and it consists in slightly diminishing the diameter of the neck or upper part of the body of such vessels, and placing a rounded or raised band at or near the point of the smallest diameter of such neck, and extending entirely around the neck. From this rounded or raised band parallel flutings extend upward to near the top of the vessel, and similar flutings extend from the rounded or raised band downward some distance to or upon the body of the vessel.

It is not essential to my design that the diameter of the vessel should be contracted at all, although I prefer to do so, as the material and substantial part of my invention consists in the employment of the band with the upward and downward extending flutings.

My design can be applied equally as well and with as good effect to dinner and tea sets. 30
What I claim as my invention is—

1. An ornamental design for vessels composing toilet-sets, consisting of parallel flutings extending from near the top of the vessel to near or about half-way down the sides of the 35 vessel, such flutings interrupted near or about the center of their length by a raised band encircling the vessel.

2. The upper flutings extending down to and interrupted by the rounded band, in combination with such band. 40

3. The lower flutings commencing at the rounded band and extending therefrom in a downward direction, and covering a portion of the body of the vessel, in combination with 45 the rounded band.

4. The rounded band interrupting the parallel flutings and extending around the vessel.

ISAAC DAVIS.
